PURIFICATION OF AQUEOUS CAUSTIC SOLUTIONS

William C. Eichelberger, Syracuse, N. Y., assignor to The Solvay Process Company, New York, N. Y., a corporation of New York

No Drawing. Application August 15, 1936,
Serial No. 96,248

11 Claims. (Cl. 204—9)

This invention relates to the purification of caustic and is particularly concerned with the removal of chlorate and bromate impurities from caustic such as that produced electrolytically.

5 In the manufacture of sodium or potassium hydroxide by electrolysis of the corresponding brine, a small amount of the chloride and, if present, the bromide appears to be oxidized under the conditions of electrolysis so that the 10 caustic product, sodium or potassium hydroxide, contains small quantities, on the order of 0.5% and 0.2% respectively of the corresponding halates, as impurities therein. The presence of these compounds is objectionable if the caustic 15 product is to be applied to certain uses.

It is an object of the present invention to reduce the halate content of caustic products to an unobjectionable amount or to effect its substantially complete elimination.

20 In accordance with the present invention it has been found that the halate impurities in caustic solutions, even though present in exceedingly small amounts, on the order of a fraction of a percent, may be reduced to the corresponding halide by suitable electrolytic treatment of the caustic. During the electrolysis a small amount of a copper salt is continuously or substantially continuously added to the solution being electrolyzed. Cupric chloride dihydrate 25 (CuCl₂·2H₂O) has been found to be highly satisfactory.

The electrolysis apparently forms alkali-metal chloride from the cupric chloride and precipitates copper upon the cathode. The only material introduced into the solution and which is not removed by the electrolysis, therefore, is the alkali-metal chloride. Since alkali-metal chloride is already present in electrolytic caustic, the chloride added may be removed therewith by 30 any of the conventional methods for its removal.

The rate of addition of the cupric chloride should be regulated to conform to the current passing through the solution. For dilute caustic a rate of about 2 grams CuCl₂·2H₂O (representing $\frac{1}{11}$ gram copper) per hour per ampere is most suitable. For 50% caustic a rate between 45 about $\frac{1}{4}$ and $\frac{1}{2}$ gram of the cupric salt (representing $\frac{1}{11}$ to $\frac{2}{11}$ gram of copper) per hour per ampere of current preferably is used. The addition of the copper salt to the solution should be substantially continuous as a substantial increase or decrease in the rate of addition diminishes the effectiveness of the purification. For purification of sodium hydroxide of around 50% concentration a rate of cupric chloride addition cor-

responding to $\frac{1}{2}$ gram CuCl₂·2H₂O per hour per ampere has been found satisfactory. In the case of potassium hydroxide solutions the same rate has been found to be very effective until the proportion of halate present has been reduced to about 0.08% calculated as KClO₃. Below this concentration the rate of addition of cupric chloride should be diminished to equal about $\frac{1}{4}$ gram CuCl₂·2H₂O per hour per ampere. During the electrolysis of concentrated caustic solutions 10 with the continuous addition of cupric chloride, the copper, as noted above, is plated out onto the cathode. The deposit is a spongy form of copper, which, however, does not adhere to the electrode and may be readily washed therefrom 15 and settled from the caustic solution.

Since the copper salt is added to the caustic solution until the desired removal of halate has been obtained, the caustic solution would contain a small quantity of copper if the electrolysis were immediately discontinued. In order to eliminate this small proportion of copper, it is advantageous to continue the electrolysis for a substantial period thereafter. In this manner the copper content may be reduced to less than 20 0.0001% and accordingly for practical purposes the caustic may be regarded as free of copper. In a series of actual tests on caustic soda liquor, the copper content was found to be not more than 0.00005% in any case.

The efficiency of purification varies markedly with changes in temperature and it has been found desirable to carry out the process at an elevated temperature. Thus, in the purification of caustic soda solutions it has been found that 35 the rate as well as the completeness of chlorate removal is increased by increasing the purification temperature from around 60° C. to between 100° and 110° C. (With a caustic soda solution of about 8% NaOH, the rate of chlorate removal 40 is about half as great at 60° C. as at 100° C. until the chlorate, ClO₃, concentration is reduced to about 0.3 gram per liter; then the relative rate at 60° C. is still lower. With a 50% NaOH solution the rate of chlorate removal is 45 about two-thirds as great at 60° C. as at 105° to 110° C. until the chlorate concentration is reduced to about 2.6 grams per liter; then the rate at 60° C. decreases rapidly so that practically no more chlorate is removed.) Hence it is preferred 50 to carry out the process with solutions having a caustic concentration around 50% at a temperature in the neighborhood of 100° to 110° C. Higher temperatures may be employed to advantage if desired. In view of the substantial

vapor pressure of 50% solutions at higher temperatures, however, it is preferable when such temperatures are employed, to carry out the process under such conditions as to inhibit excessive vaporization. For temperatures in the neighborhood of 100° to 110° C. evaporation may take place but this is not excessive and the small amount of liquid vaporized may be replaced by the corresponding amount of water to maintain the solution concentration constant. With more concentrated solutions the vapor pressure is lower and higher temperatures are desirable. Thus with 73% NaOH a temperature of 120° to 125° C. has been used to advantage. This higher temperature reduces the viscosity of the liquid so that agitation is facilitated. With dilute solutions the temperature may be reduced to prevent ebullition if desired. Thus a temperature of 90° to 100° C. may be preferred in the case of dilute caustic to avoid boiling. The process may, of course, be carried out above the boiling point of the solution in which case it may be preferred to maintain the solution at pressures higher than atmospheric pressure to modify or prevent ebullition of the solution being treated.

While purification of dilute solutions may be effected in accordance with the process of this invention, the efficiency of the process is more or less a function of the chlorate concentration and hence for a given ratio of chlorate to caustic a high caustic concentration yields a relatively high efficiency. The process is especially effectual for the purification of solutions containing in the neighborhood of 45% to 50% caustic. As indicated in the preceding paragraph, the purification is satisfactory with more highly concentrated solutions; however, since such solutions are solid at normal temperatures, their handling presents manipulative difficulties, and it is preferred to operate with solutions which are normally liquid.

The electrolysis may be effected in any suitable apparatus having electrodes not adversely affected by the solution or causing impurities to be introduced thereinto. For this reason it is preferred to employ an anode of carbon or similarly inert material which does not go into solution to any substantial extent during the process. The cathode material is less important. Nickel, iron, or copper may be employed. The use of iron as the cathode has been found to introduce a small amount of iron into the solution and where such impurities are undesirable, and especially where a product of good color is desired, a copper or a copper plated electrode is to be preferred.

The efficiency of purification varies to a very substantial degree with variations in the anodic current density. In purifying concentrated solutions good results may be obtained with current densities between about $\frac{1}{8}$ and about $\frac{1}{2}$ ampere per square inch of anodic surface. In the case of 50% potassium hydroxide solution containing initially on the order of 0.2% potassium halate, when using a $\frac{1}{2}$ ampere per square inch anodic current density, a halate removal corresponding to 0.22 gram ClO₃ per liter per ampere was obtained in the first hour and an average rate of 0.08 gram per liter per ampere hour over the first five hour period; with a $\frac{1}{4}$ ampere per square inch anodic current density a removal equal to 0.32 gram chlorate per liter per ampere was obtained during the first hour and an average rate of 0.16 gram per liter per ampere hour over the first five hour period; and for an anodic cur-

rent density of $\frac{1}{8}$ ampere per square inch the rates were 0.30 gram for the first hour and 0.22 gram over the first five hour period. With dilute sodium hydroxide solutions (80-100 grams per liter) the optimum current density was found to be in the neighborhood of 2 amperes per square inch, whereas with 50% sodium hydroxide the optimum was found to be around $\frac{1}{4}$ ampere per square inch. A maximum efficiency for 50% caustic solutions containing an alkali-metal halate concentration in the neighborhood of 0.2% or greater, is obtained using a current density of about $\frac{1}{4}$ ampere per square inch; whereas for reducing alkali-metal halate present only to the extent of a few hundredths percent a $\frac{1}{8}$ ampere per square inch anodic current density gives the higher efficiency. It will be evident, therefore, that the anodic current density may be selected to give a maximum efficiency corresponding to the concentration of caustic and halate present in the solution and may be varied during the electrolysis so as to maintain the efficiency at the optimum.

The cathodic current density does not materially affect the efficiency of purification and accordingly the cathode area may be subservient to other practical considerations.

During the purification it is desirable to effect agitation of the solution adequate to thoroughly distribute the copper salt added and to prevent polarization of the anode. This agitation may be effected in any suitable manner as by a mechanical stirrer operating within the confines of the electrolytic cell. In some cases the solution may be heated to boiling and the violence of the boiling may be controlled to effect the desired agitation. A simple but effective means of providing adequate agitation and uniform distribution of the copper salt comprises withdrawing a portion of the liquid from the cell as a stream thereof, injecting into the stream the requisite quantity of cupric chloride and passing the stream by means of a propeller or centrifugal pump back into the cell at a point remote from that at which it was withdrawn. The rotary type pump effects a thorough admixture of the salt solution introduced with the liquid circulated and thereby provides a preadmixture of the salt solution with the caustic solution, which facilitates uniform distribution in the cell. The solution, if desired, may be returned to the cell through a nozzle to give it a relatively high temporary velocity and provide stirring of the contents of the cell. The concentration of the copper salt solution added may be adjusted so that the water supplied thereby to the caustic compensates for the water evaporated from the solution during the electrolytic purification. The amount of water to be added in this manner will, of course, depend upon the particular type of apparatus employed and the particular conditions under which the process is carried out.

The temperature of the solution during electrolysis may be kept at the optimum in any suitable manner, thus the caustic solution may be supplied in an initially heated condition and heat losses avoided by suitable insulation so that no external heating is necessary. Since the passage of the current through the solution introduces substantial heat, this is sufficient, where adequate insulation is provided, to maintain the requisite temperature. Otherwise to compensate for heat losses by radiation, conduction, etc. the electrolytic cell may be heated by the direct application of heat thereto, or, in the case of a circulatory

system, the caustic solution may be passed through a heater prior to its return to the cell. By minimizing vaporization of water from the solution, heat loss from this source may be minimized.

The following examples illustrate the process of the present invention. In the processes of Examples 1 and 2 the electrolytic cell comprises an iron vessel having its inner face copper plated and a cylindrical carbon anode driven by an electric motor so as to rotate and provide agitation of the solution in the cell. The iron vessel itself was made the cathode.

Example 1.—5400 parts of an aqueous 49% KOH solution prepared by the electrolysis of a potassium chloride brine and having a total content of bromate and chlorate corresponding to 3.04 grams per liter or approximately 0.2% KClO₃ was placed in the vessel and was heated to 107° C. by direct application of heat to the vessel. The electric current was then started and adjusted to give an anodic current density of 0.23 ampere per square inch. At the same time the addition of cupric chloride was started and adjusted at the rate of 1 gram CuCl₂·2H₂O per hour for each two amperes of current passing through the cell. The cupric chloride was added in the form of an aqueous solution containing 16.67 grams CuCl₂·2H₂O per liter. The electrolysis and the addition of cupric chloride were continued for two hours, during which the temperature was maintained at between 107° and 110° C. and the anodic current density was maintained substantially constant. At the end of the two hour period the potassium halate content of the hydroxide solution had been reduced to 1.40 grams per liter. The rate of addition of cupric chloride was then reduced to 0.5 gram per hour for each 2 amperes of current going through the cell; otherwise the conditions were maintained the same; the process thus modified was continued for four hours more. The introduction of cupric chloride solution was then discontinued and the electrolysis was continued for $\frac{1}{2}$ hour longer to eliminate copper from the solution. This also further reduced the percentage of halate present so that the final concentration of halate in the solution corresponded to 0.31 gram per liter or approximately 0.02% KClO₃. The removal of KClO₃ amounted to about 1 gram for each 1.3 ampere hours of current used with a potential drop of about 2.0 volts.

Example 2.—5400 parts by weight of an aqueous electrolytic caustic solution containing about 48% NaOH and halate corresponding to about 6.65 grams NaClO₃ per liter were introduced into the electrolytic cell and heated to a temperature of 107° C. Electric current was then started to provide an anodic current density of about 0.23 ampere per square inch and addition of cupric chloride solution (16.67 grams CuCl₂·2H₂O per liter) was begun and was maintained at the rate of $\frac{1}{2}$ gram CuCl₂·2H₂O per ampere of current flowing through the cell. The process was continued for 22 hours whereby the halate content of the caustic soda solution was reduced from 6.65 grams NaClO₃ per liter to 0.71 gram per liter, approximately 0.047%. The removal of NaClO₃ amounted to about 1 gram for each 2 ampere hours of current used with a P. D. of about 2 to $\frac{1}{2}$ volts.

Example 3.—About 3960 parts by weight of a 10% NaOH solution containing 0.78 gram per liter of halate (measured as ClO₃) were subjected to electrolysis in an apparatus of the type

above described, (except that stirring was accomplished by an auxiliary stirrer instead of by rotating the anode) at boiling temperature (105-107° C.) for a period of 7 hours using an anodic current density of about 2 amperes with an anode area of 2 square inches. A solution of CuCl₂·2H₂O, whose concentration was adjusted so that the water thereof compensated for evaporation losses, was added at the rate of 8 grams CuCl₂·2H₂O per hour, i. e. about 2 grams per ampere of current. At the end of this period 99% of the total chlorate content had been reduced.

I claim:

1. The method of reducing halate present in aqueous caustic solution containing halate, which comprises subjecting the solution to electrolysis using an anodic current density between about $\frac{1}{2}$ and about 4 amperes per square inch and gradually adding a soluble copper salt to the solution during the electrolysis at a rate between about $\frac{1}{11}$ and about $\frac{1}{11}$ gram copper per hour per ampere of current passing through the solution.

2. The method of reducing halate present in aqueous caustic solution, which comprises subjecting the solution to electrolysis using an anodic current density between about $\frac{1}{2}$ and about 2 amperes per square inch and gradually adding a copper salt to the solution at a rate between about $\frac{1}{11}$ and about $\frac{1}{11}$ gram copper per hour per ampere of current passing through the solution.

3. The method of reducing the halate content of a concentrated aqueous caustic solution, which comprises subjecting the solution to electrolysis using an anodic current density between about $\frac{1}{2}$ and about $\frac{1}{2}$ ampere per square inch and gradually adding a soluble copper salt to the caustic solution at a rate between about $\frac{1}{11}$ and about $\frac{1}{11}$ gram copper per hour per ampere of current passing through the solution.

4. The method of reducing the halate content of a concentrated aqueous caustic solution, which comprises subjecting the solution while hot to electrolysis using an anodic current density between about $\frac{1}{2}$ and about $\frac{1}{2}$ ampere per square inch and gradually adding a soluble copper salt to the caustic solution at a rate between about $\frac{1}{11}$ and about $\frac{1}{11}$ gram copper per hour per ampere of current passing through the solution.

5. The method of reducing the halate content of a concentrated aqueous caustic solution, which comprises subjecting the solution at a temperature between about 100° and about 125° C. to electrolysis using an anodic current density between about $\frac{1}{2}$ and about $\frac{1}{2}$ ampere per square inch and gradually adding a soluble copper salt to the caustic solution at a rate between about $\frac{1}{11}$ and about $\frac{1}{11}$ gram copper per hour per ampere of current passing through the solution.

6. The method of reducing the halate content of a concentrated aqueous caustic solution, which comprises subjecting the solution to electrolysis using an anodic current density between about $\frac{1}{2}$ and about $\frac{1}{2}$ ampere per square inch and gradually adding cupric chloride to the caustic solution at a rate between about $\frac{1}{11}$ and $\frac{1}{11}$ gram copper per hour per ampere of current passing through the solution.

7. The method of reducing the halate content of aqueous potassium hydroxide solution containing about 50% KOH and about 0.2% of potassium halate, which comprises subjecting the solution at a temperature between about 100° and about

110° C. to electrolysis using an anodic current density between about $\frac{1}{8}$ and about $\frac{1}{4}$ ampere per square inch and gradually adding cupric chloride to the solution at a rate corresponding to 5 about $\frac{1}{11}$ gram copper per hour per ampere of current passing through the solution.

8. The method of reducing the halate content of aqueous potassium hydroxide solution containing about 50% KOH and about 0.2% of potassium halate, which comprises subjecting the solution at a temperature between about 100° and about 110° C. to electrolysis using an anodic current density between about $\frac{1}{8}$ and about $\frac{1}{4}$ ampere per square inch and gradually adding cupric chloride to the solution at a rate corresponding to 10 about $\frac{1}{11}$ gram copper per hour per ampere of current passing through the solution, continuing said electrolysis until the potassium halate content of the solution has been reduced to about .08% 15 and thereupon diminishing the rate of addition of cupric chloride to about $\frac{1}{11}$ gram copper per hour per ampere of current passing through the solution.

9. The method of reducing the halate content 20 of an aqueous sodium hydroxide solution containing about 50% NaOH and about 0.5% sodium halate, which comprises subjecting the solution at a temperature between about 100° and about 25

110° C. to electrolysis using an anodic current density between about $\frac{1}{8}$ and about $\frac{1}{4}$ ampere per square inch and gradually adding cupric chloride to the solution at a rate of about $\frac{1}{11}$ gram copper per hour per ampere of current passing through 5 the solution.

10. The method of reducing the halate content of a dilute aqueous caustic solution, which comprises subjecting the solution at a temperature between 90° C. and the boiling point of the solution to electrolysis using an anodic current density between about 2 and 4 amperes per square inch and gradually adding cupric chloride to the caustic solution at a rate corresponding to about $\frac{1}{11}$ gram copper per hour per ampere of current 10 passing through the solution.

11. The method of reducing the halate content of an aqueous sodium hydroxide solution containing about 10% NaOH, which comprises subjecting the solution at a temperature between 100° C. 20 and the boiling point of the solution to electrolysis using an anodic current density between about 2 and about 4 amperes per square inch and gradually adding cupric chloride solution to the sodium hydroxide solution at a rate corresponding to 25 about $\frac{1}{11}$ gram copper per hour per ampere of current passing through the solution.

WILLIAM C. EICHELBERGER.
